UNITED STATES PATENT OFFICE.

URIAH CUMMINGS, OF BUFFALO, NEW YORK.

HYDRAULIC TESTING-MACHINE.

SPECIFICATION forming part of Letters Patent No. 322,800, dated July 21, 1885.

Application filed April 8, 1885. (No model.)

To all whom it may concern:

Be it known that I, URIAH CUMMINGS, of the city of Buffalo, in the county of Erie and State of New York, have invented new and 5 useful Improvements in Hydraulic Testing-Machines, of which the following is a specification.

This invention relates to an improvement in that class of machines which are employed 10 for testing the tensile strength of hydraulic cement, and has for its object to produce a simple, compact, and efficient machine for testing the tensile strength of cement briquettes by hydraulic pressure.

15 My invention consists to that end of the improvements in the construction of the machine which will be hereinafter fully set forth, and pointed out in the claims.

In the accompanying drawings, consisting 20 of two sheets, Figure 1 is a front elevation of the testing-machine having its movable jaw operated by two cylinders. Fig. 2 is an end elevation of the same. Fig. 3 is a top plan view of the same. Fig. 4 is a horizontal section in line xx , Fig. 1. Fig. 5 is a sectional elevation in line yy , Fig. 1. Fig. 6 is a front elevation of a machine having its movable jaw operated by a single piston. Fig. 7 is a top plan view of the same. Fig. 8 is a horizontal 25 section in line xx , Fig. 6. Figs. 9 and 10 are sectional elevations, at right angles to each other, of the check-valve and stop-cock interposed between the pressure-cylinder and the pressure-gage.

30 Like letters of reference refer to like parts in the several figures.

A represents the briquette made of the hydraulic cement or other material to be tested, and having the usual form—viz., enlarged end 35 portions, a , connected by a contracted neck, a' , which is to be ruptured, and which has a cross-sectional area of one square inch.

B represents the stationary jaw or base of the machine containing the working-piston C 40 and horizontal cylinder or bore c , in which the latter works. The piston C is attached to the inner end of a horizontal screw, d , which works in a threaded bushing, d' , secured in the outer end of the bore c , and carries at its outer end 45 a hand-wheel, D .

e represent two pressure-cylinders arranged vertically in the base B and connected at their lower ends with the bore c by transverse bores ff , a longitudinal bore, f' , and a vertical bore, f'' , so that the liquid which is 55 displaced from the bore c by forcing the piston C inwardly enters the pressure-cylinder e through the bores $f'f''$.

g is a depressed seat formed in the face side of the base B for the reception of one end of 60 the briquette A .

H represents the movable jaw or cross-head arranged above the base B and provided on its face side with a depressed seat, h , for the reception of the other end of the briquette, 65 the contracted neck of the latter being located between the seats g and h .

I represent two pressure-pistons secured to the movable jaw H and fitting tightly in the vertical cylinders e , so as to be raised by the 70 liquid which is forced into the cylinders e , thereby moving the jaw H away from the base and tearing the briquette. The aggregate area of the pressure-pistons I is equal to the area 75 of the contracted neck a' of the briquette.

K represents a pressure-gage connected with the upper end of the vertical bore f'' by a pipe, k , to indicate the pressure per square inch at which the briquette is torn apart.

L is a stop-cock arranged in the pipe k between the base B and the pressure-gage K . 80

l represents the casing, and l' the plug of the stop-cock L .

m represents a check-valve arranged in the pipe or conduit k below the gage K to close 85 the conduit when the pressure is removed by tearing the briquette.

n represents the valve-seat formed in the casing l above the plug l' , and n' is the valve-stem resting on the plug l' , which latter is 90 flattened on its upper side to clear the stem n' when said flattened side is in a horizontal position, and permit the valve to rest on its seat, as represented in Fig. 10.

Upon turning the screw d so as to force the 95 piston C inwardly in the cylinder c , the liquid contained in the cylinder and connecting-passages of the base B is forced against the pistons I , whereby a gradually increasing upward pressure is applied to the movable jaw 100

H until the briquette is ruptured. The liquid exerts the same pressure upon the pressure-gage which it exerts upon the movable jaw, and as soon as the briquette is ruptured and 5 the pressure in the base B is relieved the check-valve *m* closes and maintains the maximum pressure in the gage K, thereby preventing its hand from flying back. When it is desired to return the hand to the starting-point, 10 the plug *l* is turned slightly, when the flattened upper side of the plug, in turning with the plug, assumes an inclined position, and thereby serves as a lifter and raises the valve sufficiently from its seat to relieve the pressure. In this manner the pressure indicated 15 by the gage is more readily observed, and injury to the gage by the sudden removal of the pressure is avoided. The pistons I hold the movable jaw H rigidly against lateral movement, so that the movable jaw has a rectilinear movement, whereby only a straight tensile 20 strain is applied to the briquette.

In the construction represented in Figs. 6, 7, and 8 the movable jaw is actuated by a single piston, I, which moves horizontally. The 25 movable jaw is provided with horizontal bars *o* above and below the pressure-cylinder *e*, and connected with the single piston I by a vertical piece, *o'*. The stationary jaw of the 30 machine is made tubular in form, and provided with supporting-legs, *p*.

I claim as my invention—

1. In a machine for testing the tensile strength of materials by hydraulic pressure, 35 the combination, with a stationary jaw containing a working-cylinder and piston and a pressure cylinder, of a movable jaw provided with a pressure-piston, whereby the movable jaw is moved away from the stationary jaw 40 until the material which is being tested is torn asunder, substantially as set forth.

2. In a testing-machine, the combination, 45 with a stationary jaw containing a working-cylinder and piston and a pressure-cylinder,

of a movable jaw provided with pressure-piston and guided to move in a straight line and held rigidly against lateral displacement, substantially as set forth. 45

3. The combination, with the fixed jaw B, 50 provided with a working-cylinder, *c*, and piston C, and a pressure-cylinder, *e*, connected with the cylinder *e*, of the movable jaw H, provided with a pressure-piston, I, substantially as set forth.

4. The combination, with the fixed jaw B, 55 provided with upright pressure-cylinders, *e e*, working-cylinder *c*, and piston C, and a seat, *g*, of the movable jaw H, provided with a pressure-piston, I, and a seat, *h*, substantially as set forth. 60

5. The combination, with the jaws of a hydraulic testing-machine, of a pressure-gage communicating with the pressure-chamber of the jaws, and a check-valve interposed between the gage and the pressure-chamber, 65 whereby the communication is interrupted when the pressure is removed, substantially as set forth. 60

6. The combination, with the jaws of a hydraulic testing-machine, of a pressure-gage 70 communicating with the pressure-chamber of the jaws, a check-valve whereby the communication is interrupted when the pressure is removed, and a lifter whereby the valve can be raised to relieve the gage, substantially as set 75 forth. 70

7. The combination, with the jaws of a hydraulic testing-machine, of a pressure-gage, K, a check-valve, *m*, arranged below the gage, and a stop-cock, L, arranged below the check-valve and adapted to raise the same when required, substantially as set forth. 80

Witness my hand this 30th day of March, 1885.

URIAH CUMMINGS.
